UNITED STATES PATENT OFFICE.

AUGUST MULLIGAN, OF PITTSBURG, PENNSYLVANIA.

WINDOW-CLEANER FOR CARS.

No. 909,010.

Specification of Letters Patent.

Patented Jan. 5, 1909.

Application filed August 24, 1908. Serial No. 449,890.

To all whom it may concern:

Be it known that I, AUGUST MULLIGAN, a citizen of the United States of America, residing at Pittsburg, in the county of Allegheny and State of Pennsylvania, have invented certain new and useful Improvements in Window-Cleaners for Cars, of which the following is a specification, reference being had therein to the accompanying drawing.

10 This invention relates to a window cleaning device, particularly designed for the windows of a street car located in front of the motorman or operator of the car.

The primary object of my invention is to 15 provide a window cleaning device that can be easily and quickly manipulated by the motorman of the street car for removing snow, sleet, frost, water and dirt from a window, whereby his view will be unobstructed, and 20 the liability of a person being run down by the car due to the motorman's attention being obstructed reduced to a minimum.

Another object of the invention is to provide a window cleaning device that can be 25 manipulated from the platform of a car, without opening a window or leaving the platform.

My device besides being applicable to the windows located at the ends of the car is also 30 applicable to the windows of passenger railway coaches, and the windows of locomotive cabs.

The above objects are attained by a structure that will be presently described in detail 35 and reference will now be had to the drawing forming a part of this application, wherein,

Figure 1 is an end view of a portion of a street railway car equipped with my window cleaning device, Fig. 2 is a transverse sectional view of a portion of a window-sash illustrating a portion of my device, Fig. 3 is a vertical sectional view of the same, Fig. 4 is a perspective view of one of the slide bearings used in connection with my device, and Fig. 45 5 is a perspective view of a portion of a strip holder.

In the accompanying drawings, 1 designates the central window-frame of a street railway car, this window-frame having a sash 2 provided with a pane of glass 3.

To put my invention into practice, I provide the sash 2 with a rectangular frame 3^a having the side rails 4 thereof provided with a vertical groove 4^a. Attached to the rails 4, 55 at the upper ends thereof, are brackets 5 for supporting a spring roller 6 of a conventional

form. Attached to this roller and adapted to wind thereon are cables 7, which extend through slide bearings 8 movably mounted in the vertical grooves 4^a. The cables 7 are secured in the slide bearings 8 by set screws 9, and then extend downwardly through transverse openings 10 to the central portion of the frame 3^a, and from these openings the cables extend through a central opening 11 provided therefor in the sash 2. The ends of the cables are connected together and are of a length sufficient for a motorman to grip the same, pull downwardly and lower the slide bearings 8 in the grooves 4^a. To prevent wear upon the cables 7, the outer ends of the openings 10 are rounded, as at 12. The slide bearings 8 are T-shaped in elevation and one of said bearings is provided with a socket 13, while the opposite bearing is grooved, as at 14.

The socket 13 and the groove 14 are adapted to receive the ends of a strip holder, said holder comprising two flat members 15 and 16, between which is arranged a resilient strip of rubber 17. The strip of rubber 17 and the members 15 and 16 are held together by bolts 18 and nuts 19.

Set screws 20 are employed for holding the ends of the strip holder in the T-shaped slide bearings 8.

The frame 3^a is provided with a curved shield 21 for protecting the spring roller 6.

The resilient strip 17 normally engages the window-pane 3 and is held in engagement therewith adjacent to the upper edge of said window-sash by the spring roller 6. An accumulation of frost or snow upon the window-pane 3 is removed by the motorman pulling upon the cables 7, and since said cables are secured in the slide bearings 8, the resilient strip 17 will be carried downwardly over the window-pane 3. When the cables 7 are released, the spring roller 6 immediately returns the resilient strip 17 to its normal position, ready to be again used upon matter accumulating upon the window-pane 3.

It will be observed that it is only necessary to provide a window-sash with an opening in order that my device can be used in connection therewith, and that by providing the extra frame 3^a, the device can be removed during the summer months, and simply used during the winter months when the motormen are troubled by snow and similar matter coating window-panes.

In order that water and snow removed from the window-pane 3 will not accumulate

upon the frame 3^a, the lower part of said frame at the inner edge thereof is provided with a plurality of vertical openings. 22.

While in the drawings forming a part of this application there is illustrated the preferred embodiments of my invention, it is obvious that the same can be varied or changed as to shape, proportion and manner of assemblage without departing from the spirit of the invention. 10

Having now described my invention, what I claim as new, is:—

1. The combination of a frame adapted to be secured to a window sash, said frame having the side rails thereof provided with vertical grooves, T-shaped slide bearings movably mounted in said grooves, a strip holder detachably supported by said bearings, said holder comprising two members, an interposed resilient strip adapted to normally engage said window-pane, and bolts for securing said members and said strips together; a spring roller supported at the top of said frame and between said side rails, cables attached to said spring roller and adapted to

wind thereon, means for attaching said cables to said bearings, said frame having openings formed therein to receive the ends of said cables, and a shield carried by said frame for protecting said spring roller, substantially as described. 30

2. The combination of a frame adapted to be secured to a window sash, said frame having vertical grooves formed therein and further having openings, bearings slidably mounted in said grooves, a strip holder detachably connected to said bearings, a resilient strip detachably connected to said holder and adapted to engage a window-pane, a spring roller arranged in said frame 40 at the upper end thereof, and cables attached to said roller and to said bearings and adapted to extend in said openings. 35

In testimony whereof I affix my signature in the presence of two witnesses.

AUGUST MULLIGAN.
